(57) **CLAIM**

The ornamental design for a drinking cup, as shown and described.

DESCRIPTION

FIG. 1 is a top perspective view of my new design for a drinking cup;

FIG. 2 is a bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The portions of the drinking cup shown in broken line form no part of the claimed design.

1 Claim, 8 Drawing Sheets(56)
